(57) **CLAIM**

The ornamental design for a corner filler module, as shown and described.

DESCRIPTION

FIG. 1 is a top perspective view of a corner filler module showing our new design;

FIG. 2 is a bottom perspective view of FIG. 1;

FIG. 3 is a top plan view of FIG. 1;

FIG. 4 is a front plan of FIG. 3;

FIG. 5 is a right view of FIG. 3;

FIG. 6 is a bottom view of FIG. 3.

FIG. 7 is a rear view of FIG. 3

FIG. 8 is a left side view of FIG. 3; and,

FIG. 9 is a side view of FIG. 2 in an installed position in a structure.

The structure shown by dashed lines in FIG. 1 is included to illustrate an associated environment and forms no part of the claimed invention.
